UNITED STATES PATENT OFFICE.

ALVIN LOETSCHER, OF CHICAGO, ILLINOIS.

INTERNAL-COMBUSTION ENGINE.

Application filed March 18, 1922. Serial No. 544,861.

To all whom it may concern:

Be it known that I, ALVIN LOETSCHER, a citizen of the United States, and a resident of Chicago, in the county of Cook and State of Illinois, have invented certain new and useful Improvements in Internal-Combustion Engines, of which the following is a specification.

This invention relates to an improvement 10 in internal combustion engines, wherein a supply of water or water vapor is introduced into the cylinders of the engine or into the combustible charge supplied thereto.

15 The object of the invention is to provide an improvement of this character which is automatic in its operation and serves to enhance the character of the combustible charge so that the hydro-carbon contained 20 therein is completely consumed while at the same time deposits of carbon are prevented and the efficiency of the engine is in general enhanced.

Another object is to provide an improvement 25 of this character in which the supply of water is under control of an electro-magnetic means responsive to the demand of the engine whereby water is supplied to the engine only at such times and in such 30 quantities as may be necessary and proper.

Other objects and advantages reside in certain novel features of the construction, arrangement and combination of parts which will be hereinafter more particularly 35 described and pointed out in the appended claim, reference being had to the accompanying drawings forming a part of this specification, and in which,

Figure 1 is a view in elevation showing 40 the invention embodied in an internal combustion engine, and

Figure 2 is a fragmentary view partly in section and partly in elevation illustrating the valve and electro-magnetic control.

45 Referring to the drawings wherein for the sake of illustration is shown the preferred embodiment of the invention, numeral 5 designates the cylinders of an internal combustion engine which may be of any 50 conventional type and which is preferably equipped with an electric generator 6 shown as comprising a magneto but which may be dynamo or the like. The magneto is driven from the crank shaft of the engine in the conventional manner as by 55 means of the usual gearing 7. An intake

manifold 8 leads to the cylinders of the engine and includes an intake or induction pipe 9 fed from a carburetor 10 of standard design.

60 A water supply pipe 11 leads from the water jacket of the engine to the intake pipe 9 and serves to supply water from water jacket to the induction pipe as will be hereinafter more fully described. A valve casing 12 is incorporated in the pipe 11 and includes a portion 13 arranged within and completely obstructing the bore of the pipe, the portion 13 having formed thereon a conical valve seat 13^a and being provided 65 with ports 14. It is to be understood that any water which flows through the pipe must pass through the ports 14. Below the valve casing 12 a sediment plug 15 is arranged which is removable so that access 70 may be had to the ports when it is desired to clean the same.

75 A valve 16 of conical form operates in the valve casing 12 and coacts with the seat 13^a thereof and when the valve 16 snugly 80 engages the seat it closes the ports 14 and prevents flow of water therethrough. The valve 16 is provided with a stem 17 which extends up through and exteriorly of the casing 12 and within the casing a bushing 85 18 encircles the stem. Suitable packing 18^a is provided for the stem, if desired. A flanged cap 19 closes the upper end of the valve casing and preferably this flanged 90 cap is integrally formed with the bushing 18.

95 Exteriorly of the valve casing 12 the stem 17 has secured thereto a head 20 which is so constructed and arranged as to constitute the armature of an electromagnet 21 suitably supported upon the engine. The electromagnet is connected in series with the electric generator 6 by means of conductors 22.

100 A retractile coil spring 23 is arranged on the stem 17 and has one end connected to the cap 19 as at 24 and has its other end connected to the head 20 as at 25. The spring 23 tends to maintain the valve 16 closed against the action of the magnet 21.

105 If desired, a shut-off valve 26 may be incorporated in the pipe 11. This valve may comprise simply a shut-off valve or may be of the graduated port type of rotary plug valve by which the area of the flow passage 110 may be varied.

In operation, when the engine is started

and at low engine speeds, the motion transmitted to the armature of the electric generator is of relatively low velocity and therefore the current delivered to the solenoid is of relatively small value. Consequently the intensity of the magnetic field is not sufficient to attract the armature 20 against the action of the spring 23 so that the valve 16 remains closed at such times. As the speed 10 of the engine increases it is desirable that a quantity of water be introduced into the cylinders of the engine as at such times the water not only brings about complete combustion but minimizes deposits of carbon and 15 renders the engine smooth and even running while at the same time developing a maximum of speed and power with a minimum consumption of fuel. When the speed of the engine so increases the current delivered 20 from the generator to the electromagnet increases in value and consequently the intensity of the magnetic field increases to such a degree that the armature 20 will be attracted against the action of the retractile 25 coil spring 23. When the armature is so attracted it pulls the valve stem 17 and consequently the valve 16 upwardly so that the valve 16 is spaced from the valve seat 13^a and uncovers the ports 14 allowing the water 30 to pass through these ports whereby the water flows from the water jacket through the pipe 12 into the induction pipe 9 wherein it commingles with the combustible

charge. The suction or pumping effect of the pistons effects the flow of the water and this suction together with the heat to which the water is subjected in the water jacket serves to condition the water so as to better adapt it to mingle with the charge. As soon as the speed of the engine decreases the coil 40 spring 23 will return the valve to closed position and shut-off the supply of water. 35

It is to be understood that in lieu of using the water of the water jacket of the cooling system of the engine there may be provided a water tank or reservoir or other suitable source of water supply from which the pipe 11 takes its water. 45

What I claim is:

In a device for supplying moisture to an 50 internal combustion engine, a water supply pipe leading into the engine from the water jacket thereof, a valve casing incorporated in said water supply pipe and completely obstructing the bore of said pipe, said casing having ports therein within the bore of the pipe, a valve controlling said ports and having a valve stem extending exteriorly of the casing, electro-magnetic means arranged in juxtaposition to said valve casing, 55 said valve stem having a head at the outer end thereof, said head constituting an armature for the electromagnet, and a retractile coil spring associated with the valve stem and tending to retain the valve closed. 60

ALVIN LOETSCHER.
